UNITED STATES PATENT OFFICE.

REINHARD KNOBEL AND EUGEN KNOBEL, OF ST. GALL, SWITZERLAND, ASSIGNORS TO
CHARLES WALTER, OF CERNAY, HAUT RHIN, FRANCE.

POWER LOOM.

Application filed March 14, 1924, Serial No. 699,180 and in Switzerland March 20, 1923

The invention relates to power-looms for weaving and more particularly to devices on power looms to replace automatically a shuttle, on the breakage of a weft thread etc. by 5 means of a cam shaft driven, from the loose pulley of the power loom and to start the loom again.

The devices of this class which have been proposed heretofore are adapted to be used 10 only for power looms of a certain class and said devices have to be altered materially if they are to be used with power looms of any other type, and in the construction of new power looms special provision and reconstructions have to be made to allow the application 15 of said devices. All said devices have the drawback that the expense for mounting the devices and for the reconstruction of the loom are very high also differing in some respect 20 according to the type of loom. Moreover said devices co-operate positively with certain elements of the loom for instance with the brake co-acting with the fly wheel and on the breakage of a warp thread or of a weft thread the 25 brake cannot be brought out of action if for instance the lay of the loom is to be moved by hand, etc.

The main object of the invention is to obviate these and other drawbacks of the known 30 devices and a further object consists in the provision of such a device which stops the loom not only by replacing the shuttle but on the breakage of a weft thread or of a warp thread or by the action of the reed release and 35 so on.

A further object of the invention is to provide means which frees the shuttle before the same is thrown by the picker.

A still further object of the invention is to 40 provide means to repeat the action of the cutting-tool cutting the weft threads after the change of the shuttle to ensure the severing of the thread.

With these and other objects in view the invention 45 consists in the particular construction and arrangement of parts as herein set forth and claimed in the appended claims.

One preferred form of construction is shown in the drawings by way of an example.

50 In the drawing:

Fig. 1 is a side elevation of part of a power-loom while at rest, seen from that side on which the stop motion is arranged.

Fig. 2 is a front view of a part of the loom.

Fig. 3 is a plan view of a part of the loom 55 shown in Fig. 2.

Fig. 4 shows in side elevation part of the loom in the working position.

Fig. 5 is a side elevation of the device to cut 60 the weft threads and

Fig. 6 is a plan view thereof.

Fig. 7 is a sectional elevation of the shuttle box.

Fig. 8 is a side view thereof and

Fig. 9 a plan view of said shuttle box.

Fig. 10 illustrates a device to change the shuttle for an underpick loom.

Fig. 11 shows a detail thereof in side elevation and in section and

Fig. 12 is a front view.

In the drawings 1 denotes the side of the loom on which the stop motion is arranged. 2 denotes the other side of the loom, and between the sides 1 and 2 the breast beam 3 is arranged, in the well known manner.

The loom is provided with a loose pulley 4, a fast pulley 5, and a fly wheel 6. On the fly wheel 6 rests a steel band 7 serving as a brake, one end of said band 7 being fixed to a bar attached to a support 8 of the loom frame, the other end of the band 7 being adjustably attached to a lever 9 pivoted on said support 8. The lever 9 is provided with notches in any one of which a counterweight 10 may be placed. The free end of lever 9 rests on a collar 12 adjustably 85 fixed on a vertical rod 11. The rod 11 is linked to brake lever 13 pivoted to a downwardly projecting extension of plate 14.

The plate 14 rests on the part 1 of the frame and on a support 15. The lever 13 carries a pawl 16 adapted to grip over a stop 17 fixed to plate 14. On the support 8 a bearing 20 is fixed in which a flexible shaft 21 is journalled.

On the shaft 21 is rigidly connected a worm wheel 22 and on the boss of the loose pulley 4 a worm 23 is keyed which meshes with said worm wheel 22.

The shaft 21 transmits the motion of the loose pulley 4 by means of bevel gears 24 to a cam shaft 25. One of the gears 24 may be 100

brought in or out of gear by means of a shifting lever 26. The lever 26 is operated by a weighted lever 27 which latter is linked to a starting lever 29 by means of a rod 28. The 5 starting lever 29 which is pivoted at a lug of the plate 14, is provided with a cam 30 which rests on the back side of a feeler lever 31, which serves as a latch device and a control device for the levers 29 and 35. The feeler 10 lever 31 is rotatably mounted on a stud 32 on which stud the fork lever 33 is pivoted. If the feeler lever 31 is moved forwardly, the lever 29 loses its abutment and lever 29 swings out in such a manner that the rod 28 drops 15 under the action of the weighted lever 27 and the shifttable bevel gear 24 is brought in engagement with its mate.

A lever 35 engages a notch 39 of the feeler lever 31 and may be operated either by a second control device, to wit, the fork lever 33 or by the first-named control device, to wit, the feeler lever 31. The lever 35 passes through a slot 40 of plate 14 and is connected by a spring to the frame of the loom and serves as 25 a starting and stopping lever for the loom. Said lever 35 operates a belt shifting device 36 shown in a diagrammatical manner. At the upper end of said lever 35 a pin 37 is provided which when lever 35 swings out strikes 30 against an arm 38, of the pawl 16 and disengages the latter from the stop 17, the lever 13 being now free to move. But even when lever 35 is free to move the brake cannot be brought into action as a stud 41 fixed to lever 35 35 rests still on the starting and stop lever 35. The lever 29 is provided with a pin 42 which abuts on lever 35 if the latter has been moved as aforesaid the cam 30 being out of contact with the feeler lever 31. Fig. 4 shows the 40 levers 29 and 35 in the starting position.

On the cam shaft 25 a cam 45 is fastened which operates a roller 46 journalled in an arm 47 of a rod 48. The rod 48 stands under the action of a spring 49 which presses the rod 45 48 downwardly. In the head 50 of the rod 48 a cam 51 is slidably mounted which enters a slot 52 of a segment 53 rotatably mounted on the support 56. If the rod 48 moves down again the segment 53 is rotated in the direction of the arrow P Fig. 2. At the end of its way the cam 51 releases the segment 53 50 and the latter returns to its initial position under the action of a spring 57. The motion of the segment 53 is transferred by means of 55 a chain 55 to the lever 35 which enters into the recess 39 of feeler lever 31. The lever 35 shifts the levers 13 and 29 by means of the studs 41, 42 until they assume their working position (Fig. 3). The feeler lever 31 carries the pawl 60, the fork 61 being of known construction is fastened to its lever in the well known manner.

The brake is brought into operation not 60 only to stop the loom in the changing of shuttles, but also when the lever 35 is moved

out of the recess 39, which latter may be effected by any one of three operations, namely, by the action of the reed release, the action of the weft guard as when a weft thread is broken, and the action of the warp stop motion as when a warp thread is broken and the lever 58 strikes against the projection 59 on the lay 83.

To change the shuttle the shuttle-box is 65 opened, the exhausted shuttle is pushed out of it and another shuttle is introduced. It frequently happens that the shuttle sticks with its point to the picker which occasions trouble. To prevent this an arm 86 (Figs. 7-9) is provided which is fastened to a shaft 85 which 70 shaft co-operates with the device for opening and closing the shuttle box. Arm 86 operates a lever 87 the end of which is provided with a pin engaging a slot of the arm 86. The lever 87 is pivoted at 84 to the lay 83. A 75 lever 88 is pressed on to the lever 87 by means of a spring 89 (Fig. 9). If the shuttle box is opened shaft 85 is turned in the direction of the arrow Q (Fig. 7) and the lever 88 comes to rest on the picker 90. Previously the 80 picker 90 has been pushed forward in the direction given by the arrow by means of a spring 91 and the lever 92 which lever 92 is connected to the picker 90 by a flexible connecting piece 93 (Fig. 8). The picker 90 is 85 withdrawn from the shuttle 80 in a direction opposite to arrow q until the point of the shuttle 80 is free of the picker 90. The shuttle 80 is held in its position by friction and remains in its assumed position in the shuttle 90 box until the picker strikes against it. The aforesaid action takes place as soon as the device to change the shuttle starts its action. To operate said device a cam 120 is 95 provided which cam actuates the shuttle 100 changing motion, which includes the means to open the shuttle box, the means to free the shuttle, the means to close the shuttle box, the latter operation being effected by the 105 co-operation of the spring 94a (Fig. 16).

The device for changing the shuttle according to Figs. 10 to 12 which is adapted for underpick looms comprises a cam 124 arranged on shaft 25 near the cam 120. The cam 120 operates the means to change the 110 shuttle by means of a rod 121. The rod 121 is actuated by a lever 123 with a roller 122 which latter runs on the said cam 120. The cam 124 operates a lever 125 pivoted to the 115 loom frame 2. The lever 125 is provided with a slot 126 and in the slot 126 projects a pin 127 which is fastened to the shuttle shifter 129 120 slidably mounted in a guide 128. The shifter is moved over an arc the center of which is in the axis of the lay whereby the changing 125 of the shuttle in underpick looms is made possible thereby. A spring 130 is provided to swing the lever 125 on to the lay 83.

To push-out one shuttle and to insert another one the shuttle box is opened by the rod 130

121. The picker 90 is moved away from the shuttle as described above and the shuttle is pushed out by the push rod 131 acted on by a lever 132. The shuttle pushed out falls with 5 one end on an arm 133 and afterwards with the second end on a sheet metal-guide 134 through which the shuttle passes out of the loom. The guide 134 is fastened to a wall 135 of the lay 83 on which the lever 136 with 10 the arm 133 is pivoted. If a shuttle falls on the arm 133 the falling shuttle releases a device which permits the insertion of a shuttle only after the empty shuttle has been removed. The arm 133 swings lever 136 and 15 the latter releases a lever 138 which rests on the part 137 of lever 136. The lever 138 is moved by a spring 139 into a recess 140 of the lever 136. The lever 138 by moving downward brings the pawl 141 out of the path of 20 a stop pin 142 fixed to the shuttle feeder. The lever 138 acts on an arm 143 of the pawl 141 and compresses the spring 144 when falling down. By these means it is possible to swing the lever 125 in the direction of the lay and 25 to push a shuttle from the container 148 into the shuttle box. If lever 125 starts its movement before the path is clear, it will be stopped at once by the pawl 141.

The container 146 is closed at the bottom 30 by a slide 147 with tongue 148. The lever 125 actuated by the cam 124 moves the slide 147 against the action of a spring 149 in a direction indicated by arrow S (Fig. 10) so that a shuttle passes out of the container by 35 its own weight. The slide 147 is returned to its position by the spring 149.

By inserting a shuttle into the shuttle box a pin 151 strikes against a push rod 152. The latter is provided with a wedge shaped end 40 on which a pin 153 rests. Pin 153 is rigidly fixed to the arm 138 the latter being returned to its initial position when pin 151 strikes against the rod 152. The lever 136 which stands under the action of a spring 154 and 45 therewith the catch arm 133 are thereby returned to their initial position.

On the cam shaft 25 a cam 156 is fixed which operates a rod 157. The free end of rod 157 is provided with a slot 158. Into 50 the slot 158 projects a stud fixed to a pawl 159. The pawl 159 engages a toothed gear 160 rotatably mounted on a rod 161. The rod 161 actuates the shears or nippers which have to cut the weft threads by inserting a 55 new shuttle. The known cutting devices operate mostly in conjunction with the temple and perform only one cutting motion. The device shown in Fig. 5 allows the repetition of the cutting motion the latter being performed three times. The gear 160 is provided with notches 162 into which the end of the pawl 159 may pass. If the shuttle is being changed the cam shaft 25 makes but one turn. As soon as rod 157 attains its uppermost position the lever 159 is moved out 60 of the recess 162 of gear 160. The rod 161 and the gear 160 are moved by the spring 167 and the pawl 159 comes to rest on a tooth 166. At the same time the shear is opened. The rod 161 is provided with an arm 163 and with 65 a set screw in said arm, the pawl 159 is provided with a nose 165. If the lay 83 strikes against the set screw 164 the rod 161 is drawn out of the casing and the gear 160 is advanced by one tooth whereby the shear performs a 70 cutting operation. As long as pawl 159 rests on the teeth 166, the nose 168 of rod 161 cannot engage the nose 165 of the pawl 159. After the rod 161 has been advanced thrice and after the shear has performed three times 75 its cutting motion the pawl 159 passes again into a recess 162. The nose 168 engages now nose 165 and the shear is only worked again after the pawl 159 has been lifted by the cam 156. 80

In operation, with the parts in the position depicted in Figures 1 and 2, the machine or loom is operating under normal working conditions. When the supply of thread on the shuttle becomes exhausted, the feelers 68, 70, 90 or 95 move sufficiently far into the shuttle to effect or permit a lowering of the arm 77 and the pawl 60 into engagement with the weft guard whereby the latter pushes the pawl and the lever 31 to displace the lever 35 from 95 its notch or recess 39. The arms 41 and 42 being free permit the weight arm 9 to drop and apply the band brake and also the weighted lever 27 to lower and shift the gears 24 into mesh. Simultaneously, the lever 35 100 shifts the power belt onto the loose pulley so that the latter is now rotating and driving the flexible shaft 20, 21 for rotating the cam 45. At this time the rod 121 is rising to open the shuttle box and eject the empty or exhausted 105 shuttle by rod 131; this action removing the pawl or catch 141 from the path of pin 142 to permit the lever 125 functioning and inserting a fresh shuttle into the box. Of course the lever 88 is moved against the picker 90 to offset any sticking of the shuttle thereto during the ejection of the exhausted shuttle. Following the insertion of a fresh shuttle, the cam 45 is coming into play to lift the rod 48 and elevate the dog 51 above the segment 53, and when the roller 46 rides off the lift of the cam the dog will engage the notch of the segment and impart a sharp rotary movement thereto, which, through the chain connection 55, will pull the lever 35 back into the notch or recess 39, release the brake and disengage the meshing gears 24. The lever 35, by this movement, has also shifted the power belt onto the tight or work pulley 5 115 to continue the operation of the loom. 120

What we wish to secure by U. S. Letters Patent is:

1. In a power loom, a drive shaft, fast and loose pulleys driven by said shaft, loom mechanism actuated by the fast pulley, a brake 130

device for stopping the loom mechanism, a cam shaft, gearing adapted to be actuated by the loose pulley for actuating said cam shaft, a clutch device for throwing said gearing into 5 and out of action, a shifter including a starting and stopping lever for shifting the power from the fast pulley to the loose pulley and vice versa, a control device governing the starting and stopping lever for throwing 10 said lever into action to shift the power from the fast pulley to the loose pulley, a normally inactive control lever controlling said brake device, a normally inactive control lever controlling said clutch device, co- 15 acting contact members on said starting and stopping and control levers for shifting said control levers into action when the starting and stopping lever acts on its fast to loose power shifting movement and for returning 20 said controlling levers to normal inactive position upon the return of the starting and stopping lever to normal position, and means operative by the cam shaft for returning said starting and stopping lever to normal position. 25

2. In a power loom, a drive shaft, fast and loose pulleys driven by said shaft, loom mechanism actuated by the fast pulley, a brake device for stopping the loom mechanism, a 30 cam shaft, gearing adapted to be actuated by the loose pulley for actuating said cam shaft, a clutch device for throwing said gearing into and out of action, a shifter including a starting and stopping lever for shifting the power 35 from the fast pulley to the loose pulley and vice versa, a plurality of control devices each governing the starting and stopping lever for throwing said lever into action to shift the power from the fast pulley to the loose pulley, a normally inactive control lever controlling 40 said brake device, a normally inactive control lever controlling said clutch device, co-acting contact members on said starting and stopping and control levers for shifting said 45 control levers into action when the starting and stopping lever acts on its fast to loose power shifting movement and for returning said control levers to normal inactive position upon the return of the starting and stopping lever to normal position, and means operative by the cam shaft for returning said starting and stopping lever to normal position. 50

3. In a power loom, a drive shaft, fast and loose pulleys driven by said shaft, loom mechanism actuated by the fast pulley, a brake device for stopping the loom mechanism, a shuttle change mechanism including a cam shaft, gearing adapted to be actuated by the 55 loose pulley for actuating said cam shaft, a clutch device for throwing said gearing into and out of action, a shifter including a starting and stopping lever for shifting the power from the fast pulley to the loose pulley and vice versa, a control device governing the 60

starting and stopping lever for throwing said lever into action to shift the power from the fast pulley to the loose pulley, a normally inactive control lever controlling said brake device, a normally inactive control lever controlling said clutch device, co-acting contact members on said starting and stopping and control levers for shifting said control levers into action when the starting and stopping lever acts on its fast to loose power shifting 75 movement and for returning said controlling levers to normal inactive position upon the return of the starting and stopping lever to normal position, and means operative by the cam shaft at the end of a shuttle change motion for returning said starting and stopping lever to normal position. 80

4. In a power loom, a drive shaft, fast and loose pulleys driven by said shaft, loom mechanism actuated by the fast pulley, a brake device for stopping the loom mechanism, a shuttle change mechanism including a cam shaft, gearing adapted to be actuated by the loose pulley for actuating said cam shaft, a clutch device for throwing said gearing into 90 and out of action, a shifter including a starting and stopping lever for shifting the power from the fast pulley to the loose pulley and vice versa, a plurality of control devices governing the starting and stopping lever for 95 throwing said lever into action to shift the power from the fast pulley to the loose pulley, a control lever governing said clutch device and normally held from action by one of said control devices, a normally inactive control lever controlling said brake device, contacts operative respectively upon the fast to loose and loose to fast shifting motions of the starting and stopping lever for rendering said control levers operative and for returning said levers to normal position, and means operative by the cam shaft at the end of a shuttle change motion for returning said starting and stopping lever to normal position. 100

5. A power loom as claimed in claim 1, in which the brake controlling lever and the clutch controlling lever are provided with releasing projections lying in the path of the stopping and starting lever, and in which the brake applying lever is held normally inactive by a latch released by the fast to loose pulley shifting motion of the starting and stopping lever. 115

6. A power loom as claimed in claim 1 in 120 which, in the shuttle changing action of the shuttle change mechanism, a device is operated by the shuttle change mechanism for positively pushing the picker stick out of engagement with the shuttle. 125

7. A loom as claimed in claim 1, in which in the shuttle change action the picker is positively removed by the action of the shuttle change mechanism from the shuttle simultaneously with the opening of the shuttle box. 130

8. A loom as claimed in claim 1, in which the closing and the opening of the shuttle box and the expulsion of an empty shuttle is effected by one and the same cam, which cam also frees the shuttle from the picker.

9. A loom as claimed in claim 1, in which a pawl is provided which projects in the path of a pin of the shuttle feeder which pin

is actuated by the falling of the empty shuttle to prevent the insertion of a shuttle until 10 the empty shuttle has been removed.

In testimony whereof we affix our signatures.

REINHARD KNOBEL.
EUGEN KNOBEL.
